UNITED STATES PATENT OFFICE.

HARRY P. TOWNSEND AND WILBUR R. CORBIN, OF NEW BRITAIN, CONNECTICUT, ASSIGNORS TO CORBIN CABINET LOCK COMPANY, OF NEW BRITAIN, CONNECTICUT, A CORPORATION OF CONNECTICUT.

LOCK.

No. 856,556.

Specification of Letters Patent.

Patented June 11, 1907.

Application filed January 31, 1907 Serial No. 354,973.

To all whom it may concern:

Be it known that we, HARRY P. TOWNSEND and WILBUR R. CORBIN, citizens of the United States, residing at New Britain, county of Hartford, Connecticut, have invented certain new and useful Improvements 5 in Locks, of which the following is a full, clear, and exact description.

This invention relates particularly to a 10 pin tumbler cylinder lock in which a single hub is operable by two differently bitted keys. By the use of one of the keys the hub may be turned a limited distance, which we will say is the first step. By the use of another key the hub may be turned a second 15 step, or by the use of a third key the hub may be turned both the first and the second step, thus giving to the lock a wide range of usefulness.

20 In the drawings Figure 1 is a vertical longitudinal section through the casing and hub, showing the first key in position. Fig. 2 is a front elevation of Fig. 1. Fig. 3 is a transverse section of Fig. 1. Fig. 4 is a horizontal section through the casing and hub, 25 showing the second key in position. Fig. 5 is a perspective view of the hub. Fig. 6 is a transverse section of Fig. 5. Fig. 7 is a front elevation of Fig. 5. Fig. 8 is a side elevation 30 of a master key.

In the particular form shown in Figs. 1 to 4, we have illustrated a construction in which the hub is turned the first step by one key and the second step by another key.

35 1 is a hub casing containing offset chambered tumbler casings 1^a 1^b. These parts 1^a 1^b are arranged at different angles relatively to the axis of the hub casing.

2 is the hub proper having the usual key- 40 slot and carrying pin tumbler sections.

3 4 are keys.

One step in the revolution of the hub comprises moving the hub beyond that point where the key-slot is alined with the casing 1^b.

45 It may be assumed that the key 3 is only adapted to properly set the tumblers in the casing 1^a so as to break joints and permit the hub to turn from that position; and it may be assumed that the key 4 is only adapted 50 to cause the pin tumblers in casing 1^b to break joints and permit the hub to turn from that position.

In the particular form shown, there are a

series of pin sections 5^a 5^b 5^c 5^d 5^e 5^f in the casing 1^a. In the casing 1^b there are a series 55 of pin sections 6^a 6^b 6^c 6^d 6^e 6^f. In the hub 2 there are a series of pin sections 7^a 7^b 7^c 7^d 7^e 7^f. The keys may operate on the inner ends of the latter sections either directly or indirectly through the medium of ball bearings.

In the section 1^a this peculiarity will be noted: the pins 5^b 5^d 5^f have shouldered or headed inner ends, the pin cavities therein being counterbored at their outer ends to 65 afford clearance for said shoulders or heads. The length of the pin is such that when these heads are seated the inner end of the pin will not project into the corresponding cavity in the hub. In the casing 1^b it will also be 70 noted that the relatively alternate pins 6^a 6^c 6^e 6^f are headed, and the length of these pins is such that when these heads are seated the inner ends of the pins will not project into the hub cavities.

The key 3 is so bitted as to operate only on the pins 5^a 5^c 5^e, while the key 4 is so bitted as to operate only on the pin sections 6^b 6^d 6^f. The key 3, of course, does not have to operate those pin sections in the 5 series which do 80 not engage and lock the hub, that is, the headed pin sections. The key 4 does not have to operate the headed pins of the 6 series. Inasmuch as these sets of pins, respectively, are in different cross sectional 85 planes, it follows that the keys 3 and 4 have different bittings. The key 3 will release the hub say when the several pin sections are alined with the casing 1^a, and consequently the hub can be turned in either direction 90 until the pin sections therein register with the casing 1^b, whereupon the unshouldered or headless tumblers therein will instantly drop into the cavities in the hub, locking the hub from further movement by said key 3. 95 The key 4, however, may now be employed to release the hub when in this position, so that it may be turned in either direction until the pin sections therein are alined with the casing 1^a, whereupon the parts will be 100 locked in their original position.

From the foregoing it will be seen that with a single hub two independent locking positions may be employed, for which it will require two differently bitted keys to release 105 the same. If desired, the hub may be per-

mitted to turn only in one direction. This may be accomplished by means of a simple stop 8 with a spring 8^a arranged to check the backward rotation of the hub 2. Such a lock 5 may be employed in whatever connection conditions may arise making such an arrangement desirable. It is obvious that a master key may be provided with bittings to operate both series of pins and thereby operate the 10 lock in one movement.

In Figs. 5, 6 and 7, we have shown a modified construction in which the hub may be moved from the first to the second position and back again to the original position, if desired. In this form also a master key may be used which has the capacity of releasing the hub when it is in the first position or second position, and moving it a relatively greater distance than the first key. Such a 20 construction may be employed wherever there is a demand for such a lock. For example, such a construction might be employed where the first movement could be utilized to first release a dead lock and second 25 to operate a latch bolt of any well known type. While we have not shown this pin tumbler lock in connection with such a latch mechanism, those familiar with the art will readily understand from the description how 30 the same may be applied without illustration or further explanation.

In this form of the invention, the casing, the offset chambered tumbler casings, and the pin tumblers carried therein and in the hub, 35 are the same. When the first key 3 is inserted, as above described, the hub can be turned until the pin sections therein register with the casing 1^b, whereupon the unshouldered or headless tumblers therein will instantly 40 drop into the cavities in the hub, locking the hub from further movement in either direction by the key. To permit the hub to be returned by said key to its original position, the said hub has tangential recesses 9 9 on 45 one side of the pin holes adjacent to those pin sections which would otherwise lock said hub from backward rotation. These cut-away portions form inclines which force back the pins in the section 1^b so as to permit the 50 hub to be returned by the key 3 to the original position.

The key 10 is a master key, and the biting thereon is suitable to lift all the pin sections, so that the hub may be released. The biting is also such on the master key 10 that it 55 will properly position all of the pins of the 7 series on the hub 2. The consequence is, this master key 10 may be utilized to release the hub from either position.

60 It should be stated that the function of the headed pins in all instances is to hold back the pin section in the casing so that the latter will not accidentally move inwardly so far as to lock the hub. While these headed pin sections serve in this manner, they of course

momentarily yield when forced back by the pin sections in the hub as the latter are lifted by the act of inserting or withdrawing a key.

What we claim is:

1. In a pin tumbler lock, a hub, pin tumbler sections therein, a casing, two independent series of pin tumbler sections therein arranged to coöperate alternately with the pin sections in said hub each series of pin sections adapted to be operated by separate keys for 75 rotating the hub in the same direction.

2. In a pin tumbler lock, a hub, pin tumbler sections therein, a casing, two independent series of pin tumbler sections therein arranged to coöperate alternately with the pin 80 sections in said hub, and separate means to operate each of said series of pin sections to free the hub in the same direction.

3. In a pin tumbler lock, a hub, pin tumbler sections therein, a casing, two independent 85 series of pin tumbler sections therein arranged to coöperate alternately with the pin sections in said hub, one series of independent pin sections adapted to be operated by a key for partially rotating the hub, and the 90 other series of independent pin sections adapted to be operated by a different key for further rotating the hub in the same direction.

4. In a pin tumbler lock, a hub, pin tumbler sections therein, a casing, a series of pin tumbler sections therein adapted to coöperate with the pin sections in said hub, said pin sections adapted to be operated by a key for 100 rotating said hub, an additional series of pin tumbler sections carried by said casing adapted to engage said hub when freed from said first series, and said latter series of pin sections adapted to be operated by a different key for further rotating said hub in the same 105 direction.

5. In a pin tumbler lock, a hub, pin tumbler sections therein, a casing, two independent 110 series of pin tumbler sections therein arranged to coöperate alternately with the pin sections in said hub, the first independent series of pin sections adapted to be operated by a key for releasing and rotating said hub until engaged by the other independent series of sections, said hub being cut away on one 115 side to allow the return thereof to the first position, and means carried by the casing preventing the hub when engaged by the first independent series of pin sections from being turned away from said second independent 120 series of pin sections.

6. In a pin tumbler lock, a hub, pin tumbler sections carried in cavities therein, a casing, a series of pin tumbler sections carried in cavities therein adapted to coöperate with the pin sections in said hub, some of said pin sections provided with heads engaging shoulders in the cavities in which they are mounted to prevent said pins from entering the corresponding cavities in the hub, the headless 125 130

- pin sections adapted to be operated by a key for breaking joints with the pin sections in the hub and turning the same, additional series of pin tumbler sections carried in cavities in the casing adapted to coöperate with the pin sections in said hub, said last mentioned series of pin sections adapted to be operated by a different key for freeing the hub. 5
7. In a pin tumbler lock, a hub, pin tumbler sections carried in cavities therein, a casing, a series of pin tumbler sections carried in cavities therein and adapted to coöperate with the pin sections in the hub, said series of pin sections adapted to be operated by a key 10 for freeing and turning said hub, a second series of pin tumbler sections carried in cavities in the casing adapted to coöperate with the pin sections in said hub, some of said pin sections having heads engaging shoulders 15 in the cavities in which they are mounted to prevent said pins from entering the corresponding cavities in the hub, and additional means to operate the headless pin sections to break joints with the sections in the hub to 20 free and turn the same. 25
8. In a pin tumbler lock, a hub, pin tumbler sections carried in cavities therein, a casing, two independent series of pin tumbler sections carried in cavities in said casing 30 adapted to coöperate alternately with the pin sections in said hub, some of said pin sections in each of said independent series having heads engaging shoulders in the cavities in which they are mounted to prevent said 35 pin sections from entering the corresponding cavities in the hub when alined therewith, and the headless pin sections in said casing adapted to be operated by separate keys for breaking joints with the pin sections in the 40 hub and freeing the same from first one and then the other of said independent series of pin sections. 45
9. In a pin tumbler lock, a hub, pin tumbler sections carried in cavities therein, a casing, two independent series of pin tumbler sections carried in cavities in said casing adapted to coöperate alternately with the pin sections in said hub, some of said pin sections alternating in said series having heads engaging shoulders in the cavities in which they are 50 mounted to prevent said pin sections from entering the corresponding cavities in the hub when alined therewith, the headless pin sections in said casing adapted to be operated by separate keys for breaking joints with the 55 pin sections in the hub and freeing the same from first one and then the other of said independent series of pin sections. 60
10. In a pin tumbler lock, a hub, pin tumbler sections carried in cavities therein, a casing, a series of pin tumbler sections carried in cavities therein adapted to coöperate with the cavities in said hub, the said pin sections adapted to be operated by a key for 65 breaking joints with the pin sections in the hub and turning the same, a second series of pin tumbler sections carried in cavities in the casing adapted to engage in the corresponding cavities in said hub when alined therewith to prevent further rotation, the hub being cut away on one side of the cavities engaged thereby to allow reverse rotation of said hub, and said last named series of pin sections adapted to be operated by a different key for breaking joints with the pin sections in the hub and freeing the same. 70
11. In a pin tumbler lock, a hub, pin tumbler sections movable therein, a hub casing, and two independent series of pin tumbler sections mounted in cavities therein arranged to coöperate independently with the pin sections in the hub the pin sections of the two series adapted to be operated by separate keys for rotating the hub in the same direction. 80
12. In a pin tumbler lock, a hub, pin tumbler sections movable therein, a hub casing, and two independent series of pin tumbler sections mounted in cavities therein arranged to coöperate independently with the pin sections in the hub, some of said pin sections in each series in the casing being provided with means preventing them from extending into the corresponding cavities in the hub when alined therewith. 85
13. In a pin tumbler lock, a hub, pin tumbler sections mounted in cavities therein, a casing, two independent series of pin tumbler sections therein arranged to coöperate independently with the pin sections in the hub, and a plurality of pin sections in each series in the casing provided with means preventing said pin sections from entering the corresponding cavities in the hub when alined therewith, said pins sections so positioned that no two pin sections in the two series correspond. 90
14. In a pin tumbler lock, a hub, pin tumbler sections mounted in the cavities therein, a casing, two independent series of pin tumbler sections mounted in the cavities therein arranged to coöperate alternately with the pin sections in the hub, some of said pin sections in each series in the casing being provided with means coacting with the cavities in which they are mounted preventing them from extending into the corresponding cavities in the hub when alined therewith. 100
15. In a pin tumbler lock, a hub, pin tumbler sections mounted in cavities therein, a casing, two independent series of corresponding pin tumbler sections mounted in cavities therein arranged to coöperate alternately with the pin sections in the hub, and alternating pin sections in each series in the casing provided with means preventing said pin sections from entering the corresponding cavities in the hub when alined therewith. 110
16. In a pin tumbler lock, a hub, pin tumbler sections mounted in cavities therein, a 120

casing, two independent series of corresponding pin tumbler sections mounted in cavities therein arranged to coöperate alternately with the pin sections in the hub, and alternate pin sections in each series in the casing provided with means restricting them from entering the corresponding cavities in the hub when alined therewith, the said restricted pin sections in one series alternating with the restricted pin sections in the other series.

17. In a pin and tumbler lock, a hub, pin tumbler sections therein, a casing, a series of pin tumbler sections therein arranged to coöperate with the pin sections in the hub and adapted to be operated by a key for rotating said hub, and a second series of pin sections in the casing arranged to coöperate with the pin sections in the hub to lock the same from further rotation in one direction, said second series of pin sections adapted to be operated

by a different key for further rotating the hub.

18. In a pin and tumbler lock, a hub, pin tumbler sections therein, a casing, a series of pin tumbler sections therein arranged to coöperate with the pin sections in the hub and adapted to be operated by a key for rotating said hub, a second series of pin sections in the casing arranged to coöperate with the pin sections in the hub to lock the same from further rotation in one direction, said second series of pin sections adapted to be operated by a different key for further rotating the hub in both directions, and means securing the hub against counter-rotation beyond the first of said series of pin sections.
